CLAIM

The ornamental design for an electronic educational game, as shown and described.

DESCRIPTION

FIG. 1 is a perspective view of an electronic educational game showing my new design;

FIG. 2 is a front elevational view thereof;

FIG. 3 is a rear elevational view thereof;

FIG. 4 is a top plan view thereof;

FIG. 5 is a bottom view thereof; and

FIG. 6 is a right side elevational view thereof, the undisclosed left side being a mirror image.
